CLAIM

The ornamental design for a camera as shown and described.

DESCRIPTION

FIG. 1 is a front top perspective view of a camera showing our new design;

FIG. 2 is a rear bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view taken from the encircled portion labeled "9" in FIG. 1; and,

FIG. 10 is an enlarged view taken from the encircled portion labeled "10" in FIG. 4.

The dashed-dot lines form the boundary of the enlarged portion views in FIGS. 1, 4, 9 and 10 and form no part of the claimed design. The even length broken lines shown in the drawings are included for the purpose of illustrating portions of the camera that form no part of the claimed design.
